SHIPPING CONTAINER

Application filed January 24, 1930. Serial No. 423,117.

This invention relates to shipping containers.

It is among the objects of the present invention to provide a novel and improved container, which may be readily transported in knockdown form and assembled to form a container.

A further object of the present invention is to provide in a shipping container, an improved knockdown wall section including improved means for securing the members of the wall section together, and further including means for protecting the contents against friction with the wooden panels of the wall section.

A further object of the present invention is to provide a container including improved end members which may be readily attached to the container without nailing or stapling.

A further object of the present invention is to provide a novel and improved container in which the combination and interrelation of parts is such that a simple, readily assembled container is provided and one which is particularly adapted to the demands of economic manufacture.

Other objects of the present invention will be apparent from a consideration of the following specification taken in conjunction with the accompanying drawings, in which

Figure 1 is a side elevation, partly broken away, showing one embodiment of the present invention in assembled form with the end members in position;

Fig. 2 is a top plan view, partly broken away, of that form of the invention shown in Fig. 1;

Fig. 3 is a plan view of the side section in flat position;

Fig. 4 is a sectional view taken on the line 4-4 of Fig. 3; and

Fig. 5 is a detail plan view showing the side members in cylindrical form and illustrating their end securement.

The present invention is particularly adapted for use as a container for fruit and vegetables, or the like, and by its improved construction provides a container within which the fruit or vegetables may be shipped without bruising, cutting, or other injuries,

such as are usually sustained in the use of the conventional basket now in use. The present invention further provides a sturdy container which may be easily and quickly packed and which includes vertical side walls whereby maximum receiving space is provided with minimum space required for the container.

Referring more particularly to the drawings, the container includes a body formed by the association of adjacent vertical slats 10 with outer edge reinforcing bands 11. The slats 10 are also supported intermediate their ends by a central reinforcing band 12. The body of the receptacle is adapted to be shipped in flat form with the bands 11 and 12 secured to the slats by the conventional nails, staples, or the like, as shown at 13.

When it is desired to use the container, the body is bent to form a cylinder, the extending ends 14 of the bands 11 and 12 being lapped over the opposite ends of the bands to which they may be secured by staples 17 or the like, whereby the end slats 10 of the side section are secured in abutting relation.

For co-operation with the bands 11 of the side section, there are provided inner wire securing members 15, which are parallel to the bands 11, being secured on the inner face of the slats 10 by the securing staples 13, as shown more clearly in Fig. 4. When the side section is in cylindrical form, the extended ends of the wires 15 pass over the outer surface of the opposite ends of the bands 11, as indicated at 16 in Fig. 2, and their terminal ends may, if desired, be associated with the securing staples 17 or otherwise arranged to assist in securing the side section in cylindrical form.

For protecting the fruit from direct contact with the slats 10, it is preferable to provide a paper or equivalent protecting medium 18. The protecting member 18, as illustrated in Fig. 4, has its longitudinal ends lapped over the wires 15, whereby it is secured with the wires to provide protection between the fruit within the container, and the slats 10. It will also be seen that this form of construction provides for the use of the device for grain or other similar material which

100

might otherwise pass through the normal spacings of the slats. It will be understood that the invention is not, however, confined to the use of the protecting medium. If desired, the protector may be omitted where damage to the contents by contact with the slats would be negligible.

For retaining the wires 15 in proper contact with the slats and against bulging due to the circular bending of the side section, it is preferable to bend the wire 15 together with the associated protector, if such is used, between the spaces of the slats 10, as illustrated in Fig. 5, the outwardly bent portions 19 of the wire and protector lying between the spaces of the slats to provide for the taking up of slack in the bending of the flat side section.

For closing the ends of the cylindrical body, there is provided a pair of end members of improved construction. The device is seen to be double ended and the end members are uniform so that either end may be used as the top of the device, the end members being similarly secured and similarly removable. The end members include an upper and a lower central cross strip 20 and 21, respectively. The upper cross strip 20 is provided with parallel strips 22 on either side, which lie under the under cross strip 21. The cross strip 21 is provided with parallel strips 23 on either side, which are positioned under both the cross strip 20 and its parallel strips 22. Associated with the extremities of the strips 20 and 22, beveled terminal members 24 are provided, which form in conjunction with similar terminal members 25 carried by the ends of the strips 21 and 23, an internal substantially continuous rim-engaging flange 40 for the cover member, the beveled edge of which is adapted to be in supporting contact with the inner surface of the slats 10. It will be understood that the ends of the strips are suitably secured by nailing or stapling to the terminal members 24 and 25, and that, if desired, other securement may be provided between the various strips. For securing the end members to the body, the strips 20 and 21 extend beyond the terminal members 24 and 25, respectively, the extending ends 26 of which are adapted to be received through securing handles 27 which are carried by the edges of the body, it being understood that the strips 20 and 21 are sufficiently flexible to permit them to be flexed in order to be positioned through the loops 27.

From the foregoing it will readily be seen that the present invention provides an improved cylindrical container having a side wall section adapted to be shipped in flat form, together with novel and improved reinforcing means for the side section which may be used for securing the section in cylindrical form, and further provides an

improved protector adapted to be carried by the side reinforcing members. It will be understood that the present invention is not confined to the specific structural details herein presented, but that numerous changes, modifications, and the full use of equivalents may be resorted to without departing from the spirit or scope of the invention as outlined in the appended claims.

What is claimed is:

1. A container of the class described, comprising a bendable wall section including vertical slats and longitudinally-extending outer reinforcing strips, said wall section further including inner bendable connecting and reinforcing members therefor, one end of said strips extending beyond the end slat to provide for the overlapping connection thereof with the opposite end of said strips, staples adapted to secure said slats with said strips and said bendable members, and a protector carried by the inner face of said wall section, said protector comprising a sheet of protecting material supported by and between said bendable members.

2. A container of the class described, comprising a bendable wall section including vertical slats and longitudinally-extending outer reinforcing strips, said wall section further including inner bendable connecting and reinforcing members therefor, one end of said strips extending beyond the end slat to provide for the overlapping connection thereof with the opposite end of said strips, staples adapted to secure said slats with said strips and said bendable members, and a protector carried by the inner face of said wall section, said protector comprising a sheet of protecting material supported by and between said bendable members, one of the longitudinal ends of said protector extending beyond the vertical slats to overlap said bendable members when the container is in cylindrical form.

3. A container of the class described, comprising a wall section of cylindrical form, including vertical slats, external securing strips, internal securing wires, and protecting means on the inner face of said wall section, said protecting means comprising a sheet of protecting material supported by and between said wires.

4. A container of the class described, comprising a wall section of cylindrical form, including vertical slats, external securing strips, internal securing wires, protecting means on the inner face of said wall section, said protecting means comprising a sheet of protecting material supported by and between said wires, and stapling means for connecting together said wires, slats and strips.

5. A container of the class described, comprising a wall section of cylindrical form, including vertical slats, external securing strips, internal securing wires, protecting

means on the inner face of said wall section, said protecting means comprising a sheet of protecting material supported by and between said wires, and stapling means for connecting together said wires, slats and strips, said container further including end closure members.

6. In a container of the class described, a bendable wall section having vertical slats and longitudinally extending reinforcing strips secured to the outer sides of the slats, inner bendable reinforcing members secured to the inner sides of the slats, and a protector disposed to the inner bendable reinforcing members.

7. In a container of the class described, a bendable wall section having vertical slats and longitudinally extending reinforcing strips at the ends of the vertical slats and secured thereto, the reinforcing strips extending beyond the ends of the vertical slats, bendable connecting and reinforcing members secured to the inner ends of the slats, and a protector disposed at the inner side 25 of the bendable wall section and secured to the bendable connecting and reinforcing members.

8. In a container of the class described, a bendable wall section having vertical slats and longitudinally extending outer reinforcing strips at the ends of the vertical slats and secured thereto, the reinforcing strips having ends extending beyond an end vertical slat, bendable connecting and reinforcing members secured to the inner sides of the slats opposite the reinforcing strips, the said reinforcing members having ends extending at the said end wall, the bendable wall being bent with the end slats adjacent each other and with the extending ends of the reinforcing members disposed between the extending reinforcing strips and the said reinforcing strips at their other ends, and means to secure the extending ends of the reinforcing strips 45 to their said other ends.

9. In a container of the class described, a bendable wall section having vertical slats and longitudinally extending outer reinforcing strips at the ends of the vertical slats and secured thereto, the reinforcing strips having ends extending beyond an end vertical slat, bendable connecting and reinforcing members secured to the inner sides of the slats opposite the reinforcing strips and having ends extending at the said end slat, a protector member disposed at the inner sides of the slats and secured to the reinforcing members, the bendable wall being bent with the end slats adjacent each other and with the extending ends of the reinforcing members disposed between the extending reinforcing strips and the said reinforcing strips at their other ends, and means to secure the extending ends of the reinforcing strips to their said 65 other ends.

10. In a container of the class described, a bendable wall section having vertical slats and longitudinally extending outer reinforcing strips at the ends of the vertical slats and secured thereto, the reinforcing strips having ends extending beyond an end vertical slat, bendable connecting and reinforcing members secured to the inner sides of the slats opposite the reinforcing strips and having ends extending at the said end slat, a protector member disposed at the inner sides of the slats at the inner sides of the reinforcing members and around the reinforcing members and between the reinforcing members and the slats, the bendable wall being bent with the inner slats adjacent each other and with the extending ends of the reinforcing members disposed between the extending reinforcing strips and the said reinforcing strips at their other ends, and means to secure the extending ends of the reinforcing strips to their said other ends.

11. In a container of the class described, a bendable wall section having vertical slats and longitudinally extending outer reinforcing strips at the ends of the vertical slats and secured thereto, the reinforcing strips having ends extending beyond an end vertical slat, bendable connecting and reinforcing members secured to the inner sides of the slats opposite the reinforcing strips and having ends extending at the said end slat and also ends extending at the other end slat, the bendable wall being bent with the end slats adjacent each other and with the first mentioned ends of the reinforcing members disposed between the said ends of the reinforcing strips and the reinforcing strips at their other ends and with the second mentioned ends of the reinforcing members disposed against the inner sides of the reinforcing members adjacent their first mentioned ends, and means to secure the said ends of the reinforcing strips to their other ends.
